UNITED STATES PATENT OFFICE.

BEN K. FORD, OF EAST ORANGE, NEW JERSEY.

TUBE.

1,287,945.

Specification of Letters Patent. Patented Dec. 17, 1918.

Application filed April 11, 1918. Serial No. 227,843.

To all whom it may concern:

Be it known that I, BEN K. FORD, a citizen of the United States, and residing at East Orange, in the county of Essex and State of New Jersey, have invented a new and Improved Tube, of which the following is a specification.

This invention relates to spirally wound tubes which may be formed on the general type of machines shown in my Patent No. 1,059,045, dated April 15, 1913, and its object is to provide a tube formed by spirally winding a band of paper or other fibrous material, in which the adjacent edges of the band are cemented together.

This invention consists in a tube made up of one or more layers, each layer being formed from a continuous band of fibrous material having its adjacent edges cemented together. It also consists in such a layer formed from a continuous band having its adjacent edges beveled and overlapping and cemented together.

In the accompanying drawing, Figure 1 is a plan and Fig. 2 an end elevation of this improved tube. Fig. 3 is a longitudinal section of the wall of the preferred form of this tube and Fig. 4 is a similar section of a modification thereof.

Similar reference characters refer to like parts throughout the several views.

Spirally wound tubes are usually made of two layers, the joints between them alternating, and with a minimum amount of glue between the two layers. The joints are not filled with glue and there are, therefore, two continuous spiral lines of weakness in each such tube along which there is only a single thickness of material.

In the present invention, the adjacent edges of each of the bands of material forming the tube are cemented together, and because of the fact that strawboard, which is the usual material for forming tubes, is usually strongest at the point where two thicknesses are cemented together, the present tube is provided with two continuous spiral lines of reinforcement. In addition thereto, the tube itself is less impervious to moisture as the usual passages are filled.

In Fig. 3, both the outer and inner bands 1 and 2 are shown formed with beveled or skived edges, which, together with the flat

contacting surfaces, are coated with cement in any desired manner before being wound into a tube. In Fig. 4, the band 3 that forms one layer has beveled edges while the band 4 has edges at right angles to its faces. In both cases, the layer 5 of cement unites the two bands while the inclined layers 6 and 7 of the cement unite the edges of the bands. While the bands 1, 2 and 3 may be beveled as in Fig. 6 before winding, I prefer to form these bands as shown in Fig. 5. Here the edges 9 and 10 of the band 8 slope down in opposite directions, and in passing to the winding machine, the glue is applied to the surface 11 alone. When the band is wound, the portion 12 of this band will be distorted and laid onto the edge 9 of the just previously wound spiral which will cause this portion 12 to be bent up, as shown in dotted lines in Fig. 5, and will bring a line of the layer of cement which has been applied to the surface 11, between the portion 12 and the edge 9. This causes the portion 12 to fill the space between the edge 9 and a true cylinder. Because of the inherent resilience of this tube material, a sufficient pressure will be maintained between the portion 12 and the edge 9 to insure a thorough uniting of the materials. No change need be made in the devices shown in my prior patent for applying the cement to the face 11 of the band.

The proportions of the materials and numbers of layers may be changed by those skilled in this art without departing from the spirit of this invention.

I claim:

1. In a tube, the combination of a continuous spirally wound band of fibrous material and cement filling the space between and uniting adjacent edges of said band, said edges being beveled.

2. In a tube, the combination of a continuous spirally wound band of fibrous material and cement filling the space between and uniting adjacent edges of said band, both of the edges of said band normally sloping outwardly of the tube toward each other but one of said edges being distorted to lie upon the other beveled edge of the next spiral to fill the space between said edge and a true cylinder.

BEN K. FORD.
